Bernard F. Weber

General Contractor & Engineers

UNITED STATES PATENT OFFICE.

BERNARD F. WEBER, OF CHICAGO, ILLINOIS.

HYDROCARBON BURNER.

Application filed June 23, 1919. Serial No. 806,037.

To all whom it may concern:

Be it known that I, BERNARD F. WEBER, a citizen of the United States, residing at Chicago, in the county of Cook and State of Illinois, have invented a certain new and useful Improvement in Hydrocarbon Burners, of which the following is a full, clear, concise, and exact description, reference being had to the accompanying drawings, forming a part of this specification.

My invention relates to improvements in hydro-carbon burners of the type which are adapted to project and atomize a stream of liquid hydro-carbon by means of a fluid under pressure. The present invention is an improvement of the burner covered by prior patent granted to me August 14, 1900.

In the operation of burners of this type which are especially adapted to feed low grade fuel oils, the oil passage is liable at times to become clogged or stopped by particles carried into same by the oil or as sometimes occurs, the oil creates a deposit at the outlet of the oil passage and reduces or completely closes the outlet orifice. These burners are generally used for burning brick, firing boilers and for heating metallurgical furnaces. Interruption of service is undesirable and should be reduced to a minimum. I have provided means whereby the closing of the burner valve not only operates to close off the fluid under pressure, but also shuts off the flow of fuel oil, thus eliminating the necessity of operating a separate valve for this purpose and in addition to this my improved burner includes the feature of very simple means for giving access to the relatively small oil feed passage in the valve stem so that the burner can be shut off and the passage opened for cleaning very quickly. Then the oil passage can be easily and quickly cleared and the burner returned to service with but a slight stoppage.

For a clear understanding of my invention and its several advantageous features, attention is directed to said accompanying drawing in which;

Figure 1 is a longitudinal central sectional view of my improved burner; and Figures 2, 3 and 4 are cross sectional views on the lines 2-2, 3-3 and 4-4 respectively of Figure 1.

The burner of my invention comprises a cylindrical casing 1 divided between its ends by a central cross partition 2 into a forward

fluid pressure chamber 3 and a rear fuel oil chamber 4.

The fluid pressure chamber 3 is supplied with fluid under pressure, such as steam or compressed air, through the supply pipe 5, and the fuel oil chamber is supplied with fuel oil under suitable pressure through the supply pipe 6.

The forward end of the burner is closed by a head 7 which is conical or tapered and is provided with a central orifice or mouth 8 for the escape of the fluid under pressure from the chamber 3.

The orifice 8 terminates in an outwardly flared portion and at its inner end or junction with the coned wall of the head 7 forms a relatively sharp angular seat 9.

For controlling the flow of the pressure fluid from the chamber 3, I provide a valve spindle 10 extending centrally through the burner and provided at its forward end with a coned valve head 11, smaller at its forward end than the inner end of the orifice and adapted to enter into said orifice more or less for regulating the flow of fluid pressure and to be seated tightly against the valve seat 9 to close off the flow entirely.

The rear end of the casing is closed by a removable head 12 provided with a central stuffing box 13 through which the valve stem 14 projects and by which the escape of fuel oil, at this point, is prevented.

For mounting the stem for longitudinal adjustment I provide a central threaded opening 14 in the middle partition 2 and the stem is provided with a threaded portion 15 fitting with-in the threaded opening 14. The partition wall 2 is provided with central extensions 16 and 17 on its front and rear sides so that the threaded contact between the partition and the stem will be long enough to prevent any flow of the pressure fluid or the fuel oil through said joint. The stem carries a handwheel 18 rigidly mounted on its rear end for manually rotating the stem for adjusting it longitudinally. The rear end 19 of the stem is square and tapered and the hand wheel is provided with a hole 20 to drive tightly upon the stem.

To feed the fuel oil from the chamber 4 to the end of the stem for projection and atomizing by the flow of fluid under pressure around the head 11, the stem is provided with a central bore 21 extending from end to end thereof and connected by radial open-

ing 22 with the chamber 4. I place these radial openings in the rear part of the threaded portion 15 of the stem and in such position that when the valve stem is screwed 5 forward to seat the head 11 on the valve seat 9 and close off the orifice 8 the feed openings 22 will be carried within the threaded opening 14, as shown in dotted lines, and the fuel oil will thus be closed off from the central 10 feed opening 21.

As explained, the central feed opening 21 extends from end to end of the stem, it is shut off or closed at its rear end by a screw 23, the screw 23 provided with a winged 15 head 24 by which it can be quickly operated and with a fixed collar 25 adapted to be seated tightly upon the extreme rear end of the stem for making a pressure tight joint at this point. The screw 23 serves to plug 20 or stop the rear end of the central oil passage 21, but I depend mainly upon the collar 25 to seal the passage at this point against the escape of the fuel oil. The collar 25 is large enough in diameter to form a shoulder 25 to prevent the removal of the hand wheel if it should become loosened on the stem.

In assembling the burner the portion 26 of the stem which fits within the stuffing box 13 slides freely through the threaded 30 opening 14.

The forward or outlet end 27 of the passage 21 is flared to correspond with the flaring of the orifice 8 so that the effect of the projection of the central stream of oil within 35 the cone shaped stream of fluid under pressure escaping around the head 11 is to cause the oil to be thoroughly atomized and projected in a spreading cone shaped stream.

If any stoppage of the burner occurs due 40 to solid particles being carried into the bore 21 or due to the accumulation of carbon at the forward end of the passage the oil can be quickly and easily shut off from the bore 21 and radial passages 22 by screwing the 45 valve stem forward, thereby not only cutting off the flow of pressure fluid through the orifice 8 but also shutting off the flow of fuel oil to the central bore 21 by reason of the radial feed openings 22 being carried within the 50 central threaded opening 14 in the central partition. No time is lost in this operation by the necessity of having to close a shut-off valve in the supply pipe 6, which is usually installed so that, in case of necessity, the 55 burner as a whole can be removed for repairs. After the stem has been screwed forward and the flow of pressure fluid and fuel oil has been shut off, it is a simple matter to open the rear end of the bore 21 by 60 removing the screw 23 and then the passage 21 can be quickly cleared by pushing a wire or rod through the passage from its rear open end.

This operation of cleaning the burner need 65 take but a very short time and the burner

can be quickly put back into service by again replacing the screw 23, thus closing the rear end of the passage 21, and then unscrewing the valve stem to the desired point.

Even if the screwing forward of the stem 70 does not close off the steam altogether, the small leakage which occurs does not make any difference. The same is true of any slight leakage of oil. The steam escapes in a direction away from the cleaning opening 75 and can do no harm. The oil leakage likewise can do no harm to the operator while he is cleaning the bore 21.

As it is obvious that different embodiments of my invention can be devised, I do not 80 limit or confine my invention to the specific structure herein shown and described, except within the scope of the appended claims.

I claim:

1. In combination, a central spindle having an axial bore for the delivery of oil, a casing defining an axial orifice for the delivery of gas adjacent the end of said spindle, said casing cooperating with said spindle upon longitudinal movement thereof 90 to simultaneously interrupt the delivery of both oil and gas.

2. In combination, a cored spindle for the delivery of a fluid medium, a casing defining an orifice for the delivery of a different medium adjacent the discharge end of said spindle, a port in said spindle for delivering fluid to the core thereof, said spindle being shaped to close said orifice upon movement of said spindle, and said casing being shaped to close said port simultaneously with the closure of said orifice. 95

3. In combination, a spindle cored through out its length for the delivery of a fluid medium, a casing defining an orifice 105 for the delivery of a different medium adjacent the discharge end of said spindle, the other end of said spindle projecting beyond said casing, said spindle being shaped to close said orifice by movement of said 110 spindle, a port in said spindle for delivering fluid to the core thereof, said casing being shaped to close said port simultaneously with the closure of said orifice, and a removable closure on the projecting end of said spindle 115 for closing said core.

4. In combination, a casing, a diaphragm dividing said casing into two chambers, a cored spindle threaded through said diaphragm, a nozzle at one end of said casing communicating with the adjacent chamber, said spindle being shaped to open and close said nozzle, a port in the portion of the spindle passing through the chamber remote from the nozzle for receiving fluid from 120 said chamber, said port being positioned adjacent said diaphragm whereby movement of said spindle to close said nozzle will close said port by moving it into said diaphragm. 125

5. In combination, a chamber, a cored 130

spindle passing through said chamber, a port in said spindle for receiving material from said chamber, a removable closure normally closing one end of said bore to 5 compel the discharge of material received from said chamber at the other end of the spindle, and means for moving said spindle

to cover said port with the wall of the chamber, to permit removal of said closure for cleaning said core.

10

In witness whereof I hereunto subscribe my name this 18th day of June, 1919.

BERNARD F. WEBER.
